UNITED STATES PATENT OFFICE.

JOSEPH HAMMER, OF LINDEN, NEW JERSEY.

DESIGN FOR A JEWELRY-DISPLAY STAND.

Application filed September 23, 1925. Serial No. 14,882. Term of patent 3½ years.

To all whom it may concern:

Be it known that I, JOSEPH HAMMER, a citizen of the United States, and a resident of Linden, county of Union, State of New Jersey, have invented a certain new, original, and ornamental Design for a Jewelry-Display Stand, of which the following is a specification, reference being had to the accompanying drawing, forming a part hereof.

Fig. 1 is a front view of a stand embodying my design, with the lower support in perspective, and Fig. 2 is a side elevation of the stand shown in Fig. 1. The stand as

shown in the drawings consists of a base and of a panel supported by the base, the panel adapted to support articles of jewelry for display on a background of a rich fabric such as velvet surrounded by a border having the decorative features shown in the drawing.

I claim:

The ornamental design for a jewelry display stand as shown and described.

In testimony whereof I have hereunto set my hand.

JOSEPH HAMMER.
